CLAIM

The ornamental design of a holder for a note pad or similar article, as shown and described.

DESCRIPTION

FIG. 1 is a top, front perspective view of a holder for note pad or similar article showing my new design;

FIG. 2 is a front elevational view;

FIG. 3 is a top plan view;

FIG. 4 is a side elevational view, the opposite side being a mirror image thereof;

FIG. 5 is a rear elevational view; and,

FIG. 6 is a bottom plan view thereof.

FIG. 1

FIG. 2

FIG. 3

FIG. 4

FIG. 5

FIG. 6
